United States Patent Office.

GEORGE HARTZELL, OF PHILADELPHIA, PENNSYLVANIA, ASSIGNOR TO
JOHN P. REIFSNIEDER, OF SAME PLACE.

Design No. 4,751, dated April 4, 1871.

DESIGN FOR ORNAMENTS FOR THE BACKS OF LOUNGES.

The Schedule referred to in these Letters Patent and making part of the same.

I, GEORGE HARTZELL, of Philadelphia, county of Philadelphia, State of Pennsylvania, have invented or produced a Design for Ornaments for the Back of a Lounge, of which the following is a specification.

Figures 1, 2, and 3 represent the back of a lounge with my ornamental designs in different positions, and varying slightly in detail although possessing the same general characteristics.

In fig. 1, for instance, one ornament consists of a scroll, A, with carved leaf-like figures *a* below, the other ornament consisting of a shell-like figure, B, and both ornaments being united with the molding on the edge of the back in a manner too clearly shown in the drawings to need explanation.

In fig. 2 there is on the back of the lounge but one ornament, which partakes of the character of the ornament A in fig. 1.

In fig. 3 the main ornament is but a duplicate of

that shown in fig. 1, the smaller ornament in that figure being repeated in fig. 3.

Claims.

1. The design for the ornament A united with the edge of the molding on the back of a lounge, substantially as described and illustrated.
2. The design for the ornament B on the back of a lounge, substantially as shown and described.
3. The whole design, consisting of the ornaments A and B, arranged substantially as described, and as illustrated in and by the accompanying drawings.

In testimony whereof I have signed my name to this specification in the presence of two subscribing witnesses.

Witnesses: GEORGE HARTZELL.
